Pierre James
ATTORNEY

UNITED STATES PATENT OFFICE.

CHARLES P. DONNELL, OF SEQUIM, WASHINGTON.

SURVEYOR'S RANGE-FINDER.

1,179,409.

Specification of Letters Patent. Patented Apr. 18, 1916.

Application filed July 19, 1915. Serial No. 40,699.

To all whom it may concern:

Be it known that I, CHARLES P. DONNELL, a citizen of the United States, residing at Sequim, in the county of Clallam and State 5 of Washington, have invented certain new and useful Improvements in Surveyors' Range-Finders, of which the following is a specification.

This invention relates to improvements in 10 range finders employed in surveying operations, and has for its object the provision of simple and conveniently operated devices, including an electrically illuminated lamp, whereby the range of the surveyor's target 15 may be known to the transit-man.

The invention is particularly applicable and useful for employment in relatively dense woods and like occasions where the targets of ordinary construction are difficult 20 to locate through the poor light and obstructions due to thick foliage and underbrush.

The invention consists in the novel construction of a range finding staff, and the combination and adaptation therewith of an 25 electrically illuminated lamp as will be fully described in the following specifications, illustrated in the accompanying drawings, and finally set forth in the appended claims.

In said drawings, Figure 1 is a front elevational view of a range staff embodying my 30 invention. Fig. 2 is a fragmentary view in longitudinal section through the said staff and with parts of the mechanism contained therein shown partly broken away. Fig. 3 is a view in longitudinal cross section on line 3—3 of Fig. 2. Fig. 4 is a fragmentary view 35 in front elevation of Fig. 1 drawn to an enlarged scale. Fig. 5 is a view in cross section on line 5—5 of Fig. 2.

40 Referring to said drawings, wherein similar reference characters denote like parts in the several views, the reference numeral 1 indicates a range staff, such as employed with my invention, having a penetrating point 2 at its lower end. Said staff is desirably formed of rolled sheet metal to afford a casing having a longitudinally arranged chamber 3 therein. Said casing is formed of symmetrical configuration with reentrantly 45 winged portions 4 on its front face separated by a vertically arranged slot 5. Adjustably movable in said chamber is a tubular battery shell 6 having a screw threaded plug closure 7 provided with a knurled thumb-piece 8. 50 Bowed springs 10 are provided at the rear of said shell, pressing against the rear of

said casing and urging said shell in frictional contact against the inner edges of said wings 4 whereby the shell is maintained in adjusted vertical positions. A metal tab 11 60 is secured to said shell and projected through the slot 5 whereby said shell may be manipulated to raise or lower the same as desired. A dry cell or other battery 12 is adapted to be introduced within said shell through the 65 opening closed by said plug 7. Said battery may be yieldingly supported at its lower end upon coil spring 13 whereby its central pole piece 15 at its upper end is maintained in contact with a conductor 16 insulated 70 from said shell. Such shell has electrical connections with the opposite pole of said battery, and is in turn electrically connected with one terminal of a miniature electric lamp 17, which is supported in socket 18 75 mounted upon the upper end of said shell. The opposite terminal of said lamp is electrically connected with a projecting metallic lug 19 which is arranged to be united in electrical circuit with the conductor 16 by 80 means of a switch member 20. Said switch member is mounted upon a spindle 21 having a finger engaging disk 22 at its opposite end which is formed with spaced notches 23 and 24 which are engageable by spring 85 detent 25 adapted to hold said switch member 20 in its closed and opened positions respectively. Said disk 22 is arranged to project outwardly from the front of the staff to be readily manipulated, while the lamp 17 is 90 arranged to project slightly beyond the slot 5 but its outermost point is arranged to be within a line drawn from the extreme forward ends of the wings 4 whereby the latter afford protection to said lamp from accidental damage. 95

The operation of the invention may be described as follows: In relatively dark situations, such as in thick woods or underbrush, my invention may be employed as a 100 substitute for the ordinary target rod or as a means of ascertaining the range in conjunction with such rod. The staff is set upright and the current from the battery 12 is caused to flow from one terminal to the other thereof by the closing of the switch member 20, as will be readily understood, 105 to illuminate said lamp. The shell may then be raised and lowered within the staff chamber through the manipulation of the member 11 until the transit man may discover it and thereby ascertain the range. 110

The invention is extremely simple in its construction, and practical and efficient in operation. It is not subject to damage by the elements, and the entire electrical connections associated with the shell 6 may be removed from the staff by simply withdrawing the same through the upper end of the staff.

While I have described my invention with some particularity as to detail, I do not intend to confine myself to the precise construction shown, as, obviously, various modifications and changes may be made within the spirit of the invention and the scope of the claims.

Having described my invention, what I claim is:

1. In a device of the class described, the combination of a staff having a longitudinally arranged chamber with a slot in its forward side, a shell movable longitudinally within said chamber provided with a lamp exposed in said slot, and an electric battery contained within said shell to energize said lamp.

2. In a device of the class described, the combination of a staff having a longitudinally arranged chamber with a slot in its forward side, a shell movable longitudinally within said chamber provided with a lamp exposed in said slot, means to retain said shell at adjusted positions within said chamber, and an electric battery contained within said shell to energize said lamp.

3. In a device of the class described, the combination of a staff having a longitudi-

nally arranged chamber with a slot in its forward side, a shell movable longitudinally within said chamber provided with a lamp exposed in said slot, an electric battery contained within said shell to energize said lamp, and a switch to control the illumination of said lamp.

4. In a device of the class described, the combination of a staff formed with a longitudinally arranged chamber and having a slotted opening into said chamber upon its forward side, said staff being formed of material having reentrantly directed wings upon either side of said opening, a lamp movable longitudinally in said chamber having its forward end projecting through said opening and contained entirely within a line drawn between the outer extremities of said wings.

5. In a device of the class described, the combination of a staff formed with a longitudinally arranged chamber having a slotted opening in its forward side, a battery shell adjustably mounted in said chamber and adapted to receive an electric battery and transmit the current therefrom, an electric lamp rigidly mounted on said shell in circuit with said battery, and a switch movable with said shell to open or close said circuit.

Signed at Seattle, Washington, this 30th day of June, 1915.

CHARLES P. DONNELL.
